CASKET CARRIER

Christy L. Berg, St. Louis, Mo.

Application September 9, 1943, Serial No. 501,633

5 Claims. (Cl. 280—43)

This invention relates to casket carriers or apparatus for facilitating interments at funerals and with reference to locating a coffin or casket upon the base of a vault designed for inclosing the coffin preparatory to lowering the assembly into a grave. In such interments and as fully explained in applicant's patent numbered 1,855,469, it is usual to position the base of the vault over the grave upon cross bars laid transversely over the grave, the dome of the vault being suspended in suitably spaced relation above the base by some suitable apparatus, such as that described in said patent numbered 1,855,469, and so as to enable the pall-bearers to deposit the coffin or casket upon the vault base and below the dome, after which the dome is lowered over the coffin to its seat upon the base, and the whole lowered into the grave.

For the operation of locating and depositing the coffin upon the vault base, the skill and manual handling of the pall-bearers has heretofore been relied upon. But this method is more or less inconvenient to the pall-bearers owing to the limited space for the work, and the obstructions offered by the supports of the lowering apparatus.

It is the chief object of the present invention therefore to provide means for facilitating placing the coffin upon the vault base, and whereby this operation may be conveniently effected by one man alone.

Another object of the invention is to provide a light caster or wheel-borne frame or dolly arranged for supporting the forward end of a coffin in the process of trundling it over and locating it properly upon a vault base, the rear portion of the coffin being simultaneously supported upon rollers located upon the forward end of the vault base, and whereby these two accessories in combination enable the coffin to be conveniently rolled endwise to its location upon the vault base by the relatively slight effort of one man alone, the apparatus including means for conveniently removing the dolly from beneath the forward end of the coffin after the latter has been properly located upon the vault base.

Another object of the invention is to provide a dolly or casket carrier for carrying the forward end of a coffin or casket upon and along a vault base while the rear portion thereof is carried upon rollers removably mounted at the forward or approach end of the base, the said dolly or carrier comprising a pair of sectional or two-part end members with the parts of each member pivotally connected medially to form collapsible or

buckling supports at each end of the dolly, the dolly including cross rods for transversely connecting the collapsible end supports, and for carrying the forward end of a coffin along and over a vault base, and then through its collapsible structure depositing the frontal end of the coffin upon the vault base simultaneously with the rear end of the coffin passing off the rollers and onto the vault base, the ends of the cross rods being projected outwardly of the end supports, and means for releasably latching the collapsible end supports, embodying the projected ends of the cross rods, for bolstering the end supports to their normal operative position for supporting a coffin end as stated, or for collapsing the supports for removing the dolly from beneath the coffin, after the latter has been properly located upon the vault base.

The drawing shows a preferred embodiment 20 of the invention, wherein

Figure 1 is an end elevation of the dolly as in operative position upon one end of a vault base, the rest of the base being broken off.

Figure 2 is a frontal fragmental view of the 25 dolly and vault base, showing one side of the base with one end of the dolly located thereon.

Figure 3 is a top plan view of the dolly alone.

Figure 4 is a perspective view of the dolly as 30 riding upon the rear end of a vault base, showing in dotted lines the broken off end of the coffin as supported upon the dolly.

Figure 5 is a side elevation of the forward or approach end of the vault base showing rollers removably mounted thereon for supporting the 35 medial portion of the coffin, as indicated in dotted lines.

Figure 6 is a side elevation of the rear end of a vault base, showing the dolly and coffin advanced thereon to location, showing the dolly as 40 buckled upward medially for freeing the latch bars for lowering the dolly and depositing the coffin upon the vault base.

Figure 7 is a view similar to Figure 6, showing the dolly as lowered or collapsed at its medial 45 portions for depositing the end of the coffin upon the riser blocks of the vault base, for removal of the dolly.

The invention is designed for use upon the base B of a burial vault (not shown), in the process 50 of an interment, and the invention comprises a caster or wheel-borne dolly or carrier represented generally at 5, and which includes at each end a sectional or two-part supporting member 6, each section or part of each supporting mem- 55 ber including spaced triangular plates 7, 7a, sup-

ported in parallel relation by bolts 8, 8a, 8b, which are passed fixedly through the plates. The plates of one section or part of each supporting member, as the plates 7a are positioned closer together than the plates 7 of the complementary supporting member, and the tapered corners of the plates 7a are passed within the similarly turned and tapered corners of the complementary plates 7, and are there pivotally connected by the bolts 8b passed through both sets of plates. The outer ends of the medial bolts 8a of the plates 7a are extended as shown, and upstanding pivot pins 9 are seated on these ends. Latch bars 10 are bored through at one end and thereby pivotally seated over the pins 9. Coil springs 11 are seated over the upper ends of the pins and secured by nuts 9a upon the threaded ends of the pins. The bars 10 extend over to and rest upon the extended ends of the medial bolts 8a of the complementary plates 7. Thus the bars 10 may be swung out from the plates for collapsing the supporting members or may be turned inward for latching the members to their operative position. Casters 12 mounted upon the lower bolts 8 between the plates, carry the dolly.

The plates 7, 7a, at each end are bored through in alignment near their inner points and outwardly of the common pivot bolts 8b, as shown at 7b, and a pair of carrying rods 13, 13a are passed transversely and slidably through these holes at each end, thereby operatively connecting the members 6 in laterally adjustable relation and stably supporting the dolly in use. The rods 13, 13a normally extend or protrude outwardly of the supporting members 6, so that when the latch bars 10 are closed inwardly to the outer plates 7, 7a, with the free ends of these bars resting on the extended ends of the bolts 8a of the plates 7 (Fig. 3), then the outwardly extended ends of the rods 13, 13a, may rest upon the upper sides of the latch bars at each end of the dolly, thereby preventing the complementary sections or parts of the end supporting members 6 from collapsing downwardly at their inner and pivotally connected corners, and maintaining them to their upstanding and operative position, as required in the process of carrying a coffin.

A pair of short, flat arms 14 are rigidly bolted as at 15 to the plates 7, adjacent the widened ends thereof and are extended angularly upward and outward in exact transverse alignment. A push rod 16 is threaded at its ends and is passed freely through holes 14a formed through the outer free ends of the arms 14. Nuts 17 upon these threaded ends of the rod 16, at each side of the two arms, enable the end supporting members 6 to be adjusted inwardly or outwardly along and upon the carrying rods 13, 13a, for the purpose of accommodating the device to various sizes or widths of coffins.

Sockets 18 are formed in laterally spaced relation in the forward end of the base B, and a roller 19, journaled at its ends in heavy lugs 20 is provided, these lugs being formed with stems or fingers 20a at their under sides adapted for seating into the sockets 18. The base B is also formed or provided with pairs of laterally and longitudinally spaced and suitably aligned riser blocks 21, adapted to support the ends of the coffin C, when the latter is properly located upon the vault base B, and the dolly herein described is removed. The blocks 21 may be integrally formed with the vault base, or may be independent blocks laid upon the base for receiving the coffin. These blocks serve to slightly raise the coffin above the base B, and

facilitates the removal of lowering devices and straps (not shown) from beneath the coffin, after the interment has been completed.

In the use and operation of the device or apparatus described, the dolly or carrier is positioned at the forward end or approach of the vault base, and over the riser blocks at that end. The pall bearers deposit the forward end of the coffin upon the dolly, with the end thereof abutted against the push rod 16 and resting upon the two carrier rods 13, 13a. In this arrangement the dolly is positioned with the push rod 16 turned inwardly towards the opposite end of the vault base, and with the carrier rods 13, 13a turned outwardly so as to conveniently receive the end of the coffin thereupon. One man may then take hold of and support the outer free end of the coffin, and may push the same inwardly and endwise onto the vault base, the forward end of the coffin being carried by the dolly and the rear end thereof being supported and carried upon the roller 19, after the coffin has been far enough advanced along the base for that purpose. When the coffin has been properly positioned upon the base, a short hand lever 22 may then be inserted at one end horizontally between the forward plates 7, at either end of the dolly, and over the medial bolt 8a, and underneath the adjacent carrier rod 13 (see Fig. 1), and then by bearing down upon the outer end of this lever, the sections of the supporting member 6 at that end are caused to buckle upward (see Fig. 6), pivoting upon the central bolt 8b, and then by turning the latch bar 10 outward at that end, and free of the extended ends of the carrier rods 13, 13a, the sections or parts of the supporting member 6 will collapse and fall downward (see Fig. 7), letting the end of the coffin rest upon the riser blocks 21 at that end of the base B. The described operation being repeated at the opposite end of the dolly, the forward end of the coffin is thus brought to rest fully upon the riser blocks. In the positioning of the coffin upon the vault base, the rear end of the coffin has completely rolled off the roller 19, and rests upon the riser blocks 21 at that end of the base. Thus the coffin rests entirely upon the riser blocks. The completion of the interment then proceeds in conventional manner.

While I have here shown and described a preferred embodiment of the invention, and certain structural features thereof, the said embodiment as well as the several structural features involved, may be changed or modified as desired, within the scope however of the appended claims.

55 I claim:

1. In a device of the kind described for trundling a coffin to location upon a vault base, the same comprising a pair of wheel-borne supporting members spaced apart in parallel alignment, the said supporting members each including two elongated parts hingedly connected end to end, and thus adapted at their medial portions to be either raised or lowered, a pair of carrier rods extended side by side in parallel spaced relation between the said supporting members and engaging separately at their ends the parts of the supporting members to maintain same in upright and operative position, and means for releasably locking the parts of the supporting members to their horizontally aligned and operative positions, said means including latch bars pivoted at one end at each side of the device to the outer sides of one of the laterally aligned pairs of supporting members, the free ends of the latch bars being adapted to rest upon the outwardly ex-

tended ends of bolts seated in the outer sides of the complementary supporting members, whereby the outwardly extended ends of the said carrier rods may have a medial bearing upon the latch bars for maintaining the two sets or pairs of supporting members to their horizontally aligned and operative positions.

2. A device of the kind described, comprising a low-swung, wheeled dolly including a supporting frame that may be buckled upward or downward from its normal neutral and operative position along a transverse medial line passing between the wheels, and means for releasably locking the supporting frame to its normal and operative position so as to function as a vehicle, said means including latch bars pivoted at one end to the outer sides of one buckling section of the frame and supports on the outer sides of the other buckling section for engaging the free ends of the latch bars.

3. A device of the kind described for supporting the forward end of a coffin in the process of locating same upon a vault base, the same comprising a low-wheeled vehicle including a medially parted frame having the parts thereof hingedly connected to move upward or downward at their inner portions, from their normal neutral and operative position as a vehicle, and latch bars pivoted at one end at the outer sides of one part of the frame and means on the frame for supporting the free ends of the latch bars and for maintaining the parts of the frame to their horizontally aligned and operative positions for releasably locking the frame to its normal neutral and operative position for functioning as a vehicle.

4. In a device according to claim 3, means on the frame for holding the end of the coffin against forward slippage.

5. In a device of the kind described for supporting the forward end of a coffin in moving same to location upon a vault base, the same comprising a low-wheeled dolly including a rectangular frame supported at its ends by two-part end members pivotally connected at their inner abutted ends to provide collapsible supports for the frame as a whole, each part of the two-part end members including pairs of triangular plates spaced apart and so supported upon bolts passed therethrough, the tapering ends of the parts of each supporting member being pivotally connected to move upward or downward as desired, means for releasably locking the parts of 10 the end supporting members to their aligned operative positions, carrier rods extended transversely between the aligned end supporting members and passed slidably and separately through the aligned parts of the supporting members 15 20 aforesaid, thereby operatively connecting the supporting members in laterally adjustable relation and supporting them in upright position, wheels journaled between the said triangular plates of the supporting members, at their lower 25 outer corners, a pair of short, flat arms extended upward and forward from the forward margins of the said supporting members, in transverse alignment, and a push rod threaded at its ends and passed slidably through holes in the upraised ends of the said arms, whereby this push rod may co-operate with the slidably mounted carrier rods in adjusting the lateral spread of the supporting members of the device, there being nuts upon the threaded ends of the push rod for locking same in any adjusted position.

CHRISTY L. BERG.
